Black, St. Louis Park, Minn., assignors to
Eleanor B. Pillsbury, Wayzata, Minn., trustee

Application January 11, 1943, Serial No. 109,228

Term of patent 3½ years

To all whom it may concern:

Be it known that we, Walter G. Taube and Oswald R. Black, citizens of the United States, residing, respectively, at Minneapolis, Hennepin County, Minnesota, and St. Louis Park, Hennepin County, Minnesota, have invented a new, original, and ornamental Design for a Fanciful Figure or Similar Article, of which the following is a specification, reference being had to the accompanying drawing, forming part thereof, and in which

We claim:

The ornamental design for a fanciful figure or similar article, as shown.

WALTER G. TAUBE.
OSWALD R. BLACK.
